BADGE

Melvin M. Ewen, Minneapolis, Minn.

Application August 29, 1952, Serial No. 21,233

Term of patent 14 years

(Cl. D29—2)

To all whom it may concern:

Be it known that I, Melvin M. Ewen, a citizen of the United States of America, residing at Minneapolis, in the county of Hennepin and the State of Minnesota, have invented a new, original, and ornamental Design for a Badge, of which the following is a specification, reference being had to the accompanying drawing, forming a part thereof.

Fig. 1 is a front elevational view of a badge, showing my new design;

Fig. 2 is a rear perspective view thereof; and
Fig. 3 is a side elevational view thereof.

I claim:

The ornamental design for a badge, substantially as shown and described.
